UNITED STATES PATENT OFFICE.

SPENCER C. CARY, OF BROOKLYN, NEW YORK.

DESIGN FOR A BOX-STRAP.

SPECIFICATION forming part of Design No. 27,910, dated November 30, 1897.

Application filed September 27, 1897. Serial No. 653,266. Term of patent 14 years.

To all whom it may concern:

Be it known that I, SPENCER C. CARY, a citizen of the United States of America, and a resident of Brooklyn, Kings county, New York, have invented a new and original Design for Box-Straps, of which the following is a specification, reference being had to the accompanying drawings, forming part of the same, in which—

- 10 • Figure 1 is a view representing the upper face of a strip of such strapping made in my new design, and Fig. 2 is a side or edge of such strip.
- 15 The strap exhibits body portions and eyes all in one piece. The body portions are short, straight, or substantially straight, pieces bounded longitudinally by substantially straight lines connecting a series of the eyes together, and the eyes are composed of two
- 20 strands of the metal, one strand—the upper, as seen in the plan view—bounded by substantially parallel curved lines continuous with the body portions of the article, sweeping in a convex curve from one body portion to
- 25 the next body portion, and the other strand—the lower, as seen in the plan—bounded by substantially similar curved lines contacting at their ends with the lines describing the first strand, but not being continuous with
- 30 the body portion on that side where the lines of the first strand are thus continuous and their curve being set in the opposite direction to the curve of the lines bounding the first strand, the curves being sufficient to leave

between the strand an eye in a substantially 35 double convex form, the whole design representing a strap with a series of body portions bounded longitudinally by substantially straight lines and a series of eyes, the strands forming eyes appearing to be formed of horizontally-divided portions spread horizontally in curved lines, substantially as shown, and the essential features of the design are the substantially straight body portions in one piece and alternating with substantially double convex eyes horizontally set intermediate 40 the body portions, one strand defining each eye being bounded by substantially parallel convexly-curved lines continuous with the lines defining the body portion and the other 45 strand of each eye being bounded by similar curved lines reversely set, contacting but not continuous with the lines of the first strand, the material of one strand joining the body portion at a lower level than the juncture therewith of the other strand.

What I claim as my invention, and desire to secure by Letters Patent, is—

The design for a box-strap substantially as herein shown and described.

In testimony that I claim the foregoing as my invention I have signed my name, in presence of two witnesses, this 22d day of September, 1897.

SPENCER C. CARY.

Witnesses:

PETER B. VERMILYA,
A. G. N. VERMILYA.
